UNITED STATES PATENT OFFICE.

ANDREW W. QUACKENBUSH, OF PERU, INDIANA.

SMOKE-JACK.

SPECIFICATION forming part of Letters Patent No. 357,941, dated February 15, 1887.

Application filed June 12, 1886. Serial No. 204,913. (No model.)

To all whom it may concern:

Be it known that I, ANDREW W. QUACKENBUSH, of the city of Peru, county of Miami, and State of Indiana, have invented certain new and useful Improvements in Smoke-Jacks, of which the following is a specification.

As is well known round-houses for engines are provided with pipes which extend through the roof, and upon the lower ends of these 10 pipes are ordinarily-adjustable portions having flaring lower ends, which fit over the tops of the smoke stacks of the locomotives and are known as "smoke-jacks." Heretofore the means employed for elevating and lowering these smoke-jacks has usually consisted of 15 chains running over pulleys and extending to the side of the house, which are not only inconvenient but expensive.

The object of my invention is to provide a 20 cheap, convenient, and inexpensive device to take the place of such chains and pulleys for operating the jacks. This object is accomplished by pivoting a lever upon the stationary part of the smoke-pipe, connecting one 25 end by means of an appropriate link to the smoke-jack and attaching to the other end a handle by which it may be operated.

The invention further consists in means for securing this lever in position, and thus holding 30 the smoke-jack at the desired elevation, said means in this case being shown as a weight which automatically shifts its position as the lever is moved up and down, and thus serves to hold the smoke-jack up when the lever is 35 down, as will be hereinafter more particularly described.

Referring to the accompanying drawings, which are made a part hereof, and on which similar letters of reference indicate similar 40 parts, Figure 1 is a perspective view of the pipe, smoke-jack and my improved means for operating the latter, the connection between the smoke-jack and lever inside the pipe being indicated by dotted lines; Fig. 2, a detail sectional view looking toward the right from the dotted line 2 2 in Fig. 1; Fig. 3, a view on a somewhat enlarged scale of the handle; and Fig. 4, a transverse sectional view of the lever as seen when looking to the left from the 45 dotted line 4 4 in Fig. 1.

In said drawings, the portions marked A represent the permanent portion of the smoke-

pipe; B, the smoke-jack; C, the lever; D, the weight, and E the handle.

The pipe A is the ordinary pipe, secured in 55 the roof of the engine-house or round-house. It has a bearing, a, secured thereto for the pivot of the lever. The smoke-jack B is also substantially of the ordinary construction, and its straight portion preferably fits inside the 60 lower end of the pipe A. It is preferably provided with appropriate ears, b, which extend up and approach each other at the upper end inside; or it may instead have the ears secured to the outside, if the lever is arranged 65 to operate on the outside.

The lever C is mounted on a pivot, c, in the bearing a, and preferably extends through a slot in said bearing and said pipe A to the inside of said pipe, where it is connected by 70 means of a pivot, c', to the link C' on the smoke-jack B. This link C' has several holes in its lower end, and is connected to the ears B' on the smoke-jack B by means of a pivot, b', which extends through holes in said ears 75 and one of the holes in this link. Thus it may be connected at either of several points, and the elevation of the smoke-jack thus varied at pleasure.

The weight D is preferably in the form of a 80 ball, and rests on the top of the lever C, being held thereon by guide-rails D', secured to said lever, or some other appropriate means, such as a pipe or trough-shaped way. The lever is so arranged, as shown, that when it is pushed 85 up the inner end is lower than the outer end, and consequently said ball will roll toward said inner end, when the weight of the smoke-jack will overbalance that of the weight and lever and hold said lever down. When it is 90 desired to raise said smoke-jack, however, the outer end of said lever is pulled down until it is at a lower level than the inner end, when the ball will roll to said outer end and overcome the weight of the smoke-jack, which 95 is thus held at its elevated position, and the pull on the handle can then be released.

The handle E is mainly a rod connected to the outer end of the lever by a pivot, e, as shown, and is provided with an appropriate 100 hand-hold, E'. It may be divided into two parts, as indicated, the lower part consisting of a tube or pipe having a slot in its side, and the upper part of a rod extending inside said

tube, and its lower end having a projection, e' , extending through said slot. Notches $e^2 e^3$ are formed alongside said slot in said tube at its upper and lower ends, respectively, and thus the handle may be made longer or shorter to the extent of the length of said slot by simply giving the tube a partial turn on the rod, moving said tube the length of said slot and reversing the turn, so that the projection e' will rest in one or the other of the notches.

Having thus fully described my said invention, what I claim as new, and desire to secure by Letters Patent, is—

1. The combination of the pipe, the smoke-jack, and a lever pivoted to said pipe and connected to said smoke-jack at its inner end, whereby said smoke-jack may be elevated or lowered by moving the outer end of said lever down or up, substantially as set forth.

2. The combination of the smoke-pipe, the smoke-jack, a lever pivoted to said pipe and connected to said jack, and a traveling weight secured to said lever, whereby when said weight is at the inner end of its path of movement the smoke-jack will overbalance said weight and lever and keep its lowest position, and when said weight is at the outer end of its path of

movement it will overbalance said smoke-jack and hold it in the elevated position.

3. The combination, with the lever C for operating the smoke-jack, of the handle E, consisting of a rod having a projection and a tube placed upon said rod and provided with a slot and notches in the side of said slot, whereby said handle may be shortened or lengthened, as desired.

4. The combination of the pipe A, having bearing a , the smoke-jack B, having ears B', the lever C, mounted on a pivot in said bearing A, a link, C', by which said lever and the ears on the smoke-jack are connected, and means of operating said lever, substantially as described.

5. The combination, with an adjustable smoke-jack and the lever for operating the same, of a shifting or traveling weight, substantially as and for the purposes specified.

In witness whereof I have hereunto set my hand and seal, at Indianapolis, Indiana, this 8th day of June, A. D. 1886.

ANDREW W. QUACKENBUSH. [L. s.]

In presence of—

C. BRADFORD,

CHARLES L. THURBER.
